REUBEN H. PLASS, OF NEW YORK, N. Y.

Letters Patent No. 88,205, dated March 23, 1869.

IMPROVEMENT IN VELOCIPEDES.

The Schedule referred to in these Letters Patent and making part of the same.

To all whom it may concern:

Be it known that I, REUBEN H. PLASS, of the city, county, and State of New York, have invented certain new and useful Improvements in Velocipedes; and I do hereby declare that the following is a full, clear, and exact description of the same; reference being had to the accompanying drawing, forming part of this specification, and in which—

Figure 1 represents, in elevation, a two-wheeled velocipede, showing one mode of applying my improved steering-apparatus;

Figure 2 shows another mode of operating the same;

Figure 3 is a top, or plan view of the machine, as shown in fig. 2;

Figure 4 is a top, or plan view of the machine, operating, in some essentials, like that represented in fig. 1, but with the steering-apparatus gearing with the rear wheel only;

Figure 5 represents the same as fig. 4, in elevation;

Figure 6 is a plan of a similar machine, with the steering-apparatus operating on the front wheel only;

Figure 7 is an elevation of the same, showing, also, my method of increasing speed on the driving-wheel;

Figure 8 is a vertical transverse section, taken on the line of the axle of the driving-wheel in fig. 7; and

Figure 9 is a modification of fig. 7.

The same parts are indicated by corresponding letters in the several figures.

This invention consists—

First, in a novel method of gearing and operating the steering-apparatus, whether applied to either one, or both, or to any number of wheels fore and aft.

Second, in a novel method of operating the driving-wheel to increase velocity, and, at the same time, reduce the excessive exercise consequent on the rapid up-and-down motion of the feet.

Third, in the fast or loose attachment of the gears with the bifurcated axle-supports of the wheel, so that either or both wheels may be affected by the steering-power, as desired.

That the construction and operation of my improvements may be better understood, I will describe them with reference to the drawing, in which—

A represents the fore wheel, and B, the rear wheel of the velocipede, which are supported on axles, passing through bifurcated brackets, C C', connected, at their upper end, with an extension-bar, D, from one to the other, through which they have a pivotal motion laterally, and are provided, at their upper ends, with bevel or spur-wheels, E E', or other mechanical equivalents, such as friction-gear, universal joints, inclined planes, or the like, through which they gear with, or are connected to, an oscillating bar, F, parallel with the coupling-bar D, or thereabouts.

To this bar F is attached the saddle, or seat G, so

that, by the rocking or lunging position of the body on the seat, motion is communicated, by means of the connections before described, to axles of the wheels, to steer the vehicle, and, at the same time, the centre of gravity of the rider is retained in a direct line over and between the axles of the two wheels, as represented more clearly in fig. 3.

In fig. 1, the machine is represented as constructed to be steered solely by the motion of the body, through the oscillating saddle.

In fig. 2, the saddle is rigidly attached to the coupling-bar D, and the pivoted end of the bifurcated axle-support, C, of the forward wheel, is provided with a detachable handle, or key, H, by which the steering may be performed by hand. This arrangement is more particularly designed for beginners, as a support for the hands; or, the key H may be applied to the front wheel of the machine, represented in fig. 1, and used to steer by hand, in combination with the motion of the body, as before described.

In figs. 4 and 5, my method of steering by gravity is represented as applied only to the rear wheel B, and in figs. 6, 7, and 8, as applied only to the front wheel, which is deemed to be preferable.

In order to increase the velocity of travel, and, at the same time, to reduce the rapid up-and-down motion of the feet, I arrange rollers, I, on either side, above the axle J of the driving-wheel A, and intermediately between the two, I and J, other rollers, K, all in contact, so that, by communicating motion to the rollers I, by the feet operating on cranks L, or either side, a more rapid motion is given to the axle J than it would have if the power were applied directly to it.

I propose to construct this friction-driving motion of rollers, which may be bound on their peripheries with rubber, leather, or other adhesive or adherent substance, and they may be borne or pressed in contact by set-screws M, or by arranging the upper rollers in slots, and providing them with a downward spring-bearing; or the same result may be produced by a similar arrangement of a small grooved pulley, n, on the axle of the wheel, and above it a larger grooved pulley, p, with a cord, band, or chain, to communicate motion from one to the other. In this arrangement, the pulley p, or the axle, should be supported in a sliding box, and the cord be kept at a suitable tension, by a spring between the axles of said pulleys, or by an adjusting-screw, to force them apart.

I am aware that gear-wheels have been used for the same purpose, but there are many objections to them in practice. These, therefore, I do not claim.

The gear-wheels E E', on the upper ends of the bifurcated axle-supports, are connected therewith in such manner that they may be caused to rotate together.

when the power is applied, or that either one may be allowed to move freely around the vertical axis of said supports, which may be effected by inserting pins, *r*, transversely through them, or by any suitable clamp, or clutch-device.

Having thus described my invention,

What I claim as new, and desire to secure by Letters Patent, is—

1. The laterally-oscillating seat, or saddle, in combination with suitable gearing, whereby the rocking or lunging of the body is made to steer the vehicle, substantially as set forth.

2. The arrangement and combination of the driving-rollers *I* and friction-rollers *K*, with the axle *J* of the driving-wheel, or rollers thereon, substantially as shown and described.

3. So connecting the gear-wheels *E E'* with the bifurcated axle-supports, that the steering-power may be applied to either one or both of said axles at pleasure, substantially as specified.

REUBEN H. PLASS.
